CLAIM

We claim the ornamental design for a sequencing instrument, as shown and described.

DESCRIPTION

FIG. 1 is a front, top left perspective view of a sequencing instrument with the display closed and in resting position, illustrating our new design;

FIG. 2 is a rear, bottom left perspective view of the design of FIG. 1;

FIG. 3 is a front elevational view of the design of FIG. 1; FIG. 4 is a rear elevational view of the design of FIG. 1; FIG. 5 is a left side elevational view of the design of FIG. 1;

FIG. 6 is a right side elevational view of the design of FIG. 1;

FIG. 7 is a top plan view of the design of FIG. 1;

FIG. 8 is a bottom plan view of the design of FIG. 1;

FIG. 9 is a front, top left perspective view of the design shown in FIG. 1 with the display in an extended position; FIG. 10 is a front elevational view of the design of FIG. 9; FIG. 11 is a left side elevational view of the design of FIG. 9;

FIG. 12 is a right side elevational view of the design of FIG. 9;

FIG. 13 is a top plan view of the design of FIG. 9; and, FIG. 14 is a bottom plan view of the design of FIG. 9.

The broken lines shown in the drawings illustrate portions of the sequencing instrument that form no part of the claimed design.
